BODY LOCK

Anthony W. Molinare, Forest Park, Ill., assignor
to Highway Trailer Company, Edgerton, Wis.,
a corporation of Wisconsin

Application April 13, 1933, Serial No. 665,871

8 Claims. (Cl. 298—38)

This invention relates to dumping vehicles, and, as illustrated, it is applied to the type in which the body is of the hopper form mounted to tilt or roll to either side of the frame for discharging its contents. The object of the invention is to provide locking means for securing the body in upright position on the frame, and to arrange such means so that it may be conveniently released for dumping the body and will automatically lock upon return of the body to normal position. The invention comprises certain features and elements of construction in combination as herein shown and described, and as indicated by the claims.

15 In the drawing:

Figure 1 is a conventional front elevation of a dumping vehicle fitted with locking mechanism embodying this invention.

Figure 2 is a side elevation of the same.

20 Figure 3 is a fragmentary end elevation similar to Figure 1 but on a larger scale for showing details of the lock construction.

Figure 4 is a vertical section taken as indicated at line 4—4 on Figure 3.

25 Figure 5 is a detail section showing another modification of the lock.

Figure 6 is a detail section taken as indicated at line 6—6 on Figure 5.

30 Figure 7 is a vertical section on a larger scale taken as indicated at line 7—7 on Figure 5.

The vehicle chosen for the purpose of illustration includes a hopper body, 1, carried on a drop frame, 2, which includes transverse rails, 3, on which the rockers, 4, of the body roll for tilting the body into dumping position at either side of the frame. An upright end portion, 5, of the frame extends adjacent each end portion, 6, of the body. This makes it convenient to provide locking means for engaging said adjacent end portions with each other for holding the body in upright position.

As shown in Figure 1, a stop member, 7, is secured to the end surface, 6, of the body to be engaged between spaced latch bolts, 8, 8. These bolts, as indicated in Figure 3, are slidably mounted in vertical guideways, 9, 9, carried by a plate, 10, which is pivotally attached at 11 to a cross member, 12, of the upright end frame, 5. Each of the bolts, 8, is urged outwardly into locking position by its spring, 13, pocketed in the guide, 9, and each of said latches has its outer end beveled at 14 so that as the hopper body, 1, is rolled back from dumping position toward its central upright position, the stop member, 7, upon contacting one of said beveled faces, 14, will depress

the latch bolt, 8, and pass it. As the body arrives at upright position said stop, 7, will encounter the other latch bolt and will be arrested thereby.

If the guides, 9, were rigidly mounted on the end frame, 5, such encounter of the stop, 7, with the bolt, 8, might cause a rebound such that the stop, 7, would interfere with the return of the depressed bolt, 8, and the body might even recoil laterally away from the locking device. To avoid this, the pivotally mounted plate, 10, which carries the bolt guides, 9, is cushioned between springs, 15, which permit limited lateral movement of the plate, 10, about its pivot, 11. Thus it is enabled to yield laterally when the stop, 7, encounters the upstanding bolt, 8, and this avoids the sudden shock of such encounter and prevents recoil of the stop, 7, from the bolt, 8, said parts moving laterally together and allowing time for the other bolt, 8, to return to locking position and engage the opposite side of the stop, 7, to confine it.

For unlocking the body, 1, to permit tilting it to one side or the other, one of the bolts, 8, is withdrawn in opposition to its spring, 13, by tensioning a cable, 16, which is guided over pulleys, 17, 18 and 19, to a point of attachment on a winding drum, 20, mounted on a rock shaft, 21, near the middle of the length of the drop frame, 2. A foot treadle, 22, is arranged for rocking the shaft, 21, and thus winding the cable, 16, onto the drum by an amount sufficient for drawing one of the bolts, 8, out of contact with the stop, 7. If the body is of symmetrical design, as indicated in Figure 2, I may provide similar locking devices at both ends on the upright frames, 5, 5, and in that event the drum, 20, will actuate two cables, 16, one extending to one of the bolts, 8, at one end of the body, and the other extending to one of the bolts, 8, at the other end, both said bolts being disposed at the same side of the longitudinal center line so that the withdrawal of both bolts will clear the way for tilting the body to one side. And, preferably, the treadle, 22, for withdrawing a given pair of bolts, will be disposed at the opposite side of the center line from the bolts, 6, so that the operator may stand at the side of the vehicle opposite that to which the load is to be dumped, and by pressing the treadle, 22, at that side, he will release the proper bolts to allow tilting of the body toward the opposite side. In the same manner a second rock shaft, 23, with the separate treadle, 24, at the opposite side of the frame, 2, controls the other pair of bolts for allowing tilting of the body in the other direction.

The lock just described serves for holding the body, 1, against lateral movement except the limited movement permitted by the cushion spring, 15, but in traveling over rough roads there is some possibility that the body may bounce upwardly from the frame rails, 3, on which it rests. To check this tendency the frame, 5, supports a short section of rail, 25, extending transversely adjacent the end portion, 6, of the body, and the body carries an abutment which may be in the form of a roller, 26, which is disposed just under said rail, 25, when the body stands in locked position.

Heretofore, in some structures of this type, 15 check chains have been provided for holding the body down on the frame, and in some instances such chains have included spring members to allow of limited lateral motion of the body. The provision of the cushion springs, 15, in association with the locking device at one or both ends of the body, and the arrangement of the horizontal check rail, 25, permit such chains to be dispensed with entirely, and thus simplify the operations required for dumping and re-locking the body.

Figures 5, 6 and 7 show a further modification operating on substantially the same principle. In this form the locking latches, 59, are mounted in the guide housing, 51, so that they are movable horizontally toward and from the end wall, 6, of the body. The housing is supported on guide rods, 52 and 53, mounted in the brackets, 54, which, in turn, are secured to the end frame, 5. Cushion springs, 55, on the rod, 52, serve to center the housing, 51, and the latch bolts, 50, while allowing the desirable lateral movement for absorbing the shock when the stop member, 60, on the end wall, 6, of the body encounters one of the bolts in coming to locking position. In this arrangement each of the bolts may be provided with a bell crank, 61, operable by means of a cable, not shown, but similar to that shown in Figure 2, and treadle-actuated in the same manner. Return springs, 62, shown in Figure 7, act through each bell crank, 61, to urge the bolts, 50, into locking position. To check upward movement of the body, the stop member, 60, is made with laterally projecting portions, 63, over which the ends of the bolts, 50, extend in locking position, as seen in Figures 6 and 7.

It will be evident that in each of the forms of my invention herein described, the locking means for holding the body upright is so arranged that the body is yieldingly anchored to the frame in this position, with capacity for limited lateral movement when the frame vibrates in response to roughness of the road; and it will also be seen that in each form of the lock this same capacity for lateral yielding increases the certainty of operation of the twin latch bolts by absorbing any tendency for the stop member to recoil from the bolt which arrests it as the parts swing into locking position. While there is shown and described certain specific structure embodying the invention, it will be manifest to those skilled in the art that various modifications and re-arrangements of the parts may be made without departing from the spirit and scope of the invention, and that the same is not limited to the particular form herein shown and described, except in so far as indicated by the appended claims.

I claim:

1. In combination with a vehicle frame and a body tiltably mounted thereon, locking means

comprising a stop member on the body and a pair of latch bolts between which said member is confined in locked position, spring means holding said bolts yieldingly at locking position, and guide means mounted on the frame in which the bolts are retractably carried for approximately horizontal movement toward and from the end of the body, said bolts and stop having surfaces formed to cooperate cam-wise so that one of the bolts is forced back by encounter with the stop to admit the latter to position between vertical surfaces of said bolts, said stop including upwardly facing surfaces disposed adjacent the under surfaces of the bolts in their locking positions, whereby the bolts serve both to hold the body at 15 upright position and to check it against vertical movement with respect to the frame.

2. In combination with a vehicle frame and a body tiltably mounted thereon, locking means for holding the body upright comprising a stop member on the body and a pair of spring projected latch bolts arranged to engage opposite faces of said member together with guide means on which said bolts are retractably carried, said guide means being mounted on the frame for 25 limited yielding movement in substantially the direction of tilting movement of the body, and being arranged for projection and retraction of the bolts in approximately horizontal direction toward and from the body, said stop member including substantially vertical surfaces engaged between said bolts and horizontal surfaces facing upwardly for encounter with the under faces of the bolts when the parts are in locked position.

3. In combination with a vehicle frame structure and a body structure tiltably mounted thereon, a lock for holding the body upright comprising a stop member secured to one of said structures and a pair of independently spring-projected latch bolts between which said stop is 40 closely confined in locking position, together with guide means for said bolts carried on the other of said structures, said lock including means for automatically retracting one of the bolts to admit the stop between them as the body is tilted into 45 upright position; a member on which said guide means is mounted for a limited lateral movement in response to the encounter of the stop and the other bolt, and spring means tending to hold the said member normally between its lateral limits 50 of movement.

4. In combination with a vehicle frame and a body tiltably mounted thereon, a lock for holding the body upright comprising a stop member on the body and a pair of independently spring-projected latch bolts between which said stop is 55 closely confined in locking position, together with guide means for said bolts carried on the frame, said lock including means for automatically retracting one of the bolts to admit the stop between them as the body is tilted into upright position; a support on which said guide means is mounted for limited lateral movement in response to the encounter of the stop and the other 60 bolt, and spring means tending to hold the guide means normally midway between its lateral limits 65 of movement.

5. In combination with a vehicle frame and a body tiltably mounted thereon, a lock for holding the body upright comprising a stop member on the body and a pair of independently spring-projected latch bolts between which said stop is closely confined in locking position, together with guide means for said bolts carried on the frame, 70

said lock including means for automatically re-
tracting one of the bolts to admit the stop be-
tween them as the body is tilted into upright
position; a member on which said guide means
is carried, said member being pivotally mounted
5 on the frame for limited lateral movement in
response to the encounter of the stop and the
other bolt, and spring means reacting between
said member and the frame for yieldingly per-
mitting such movement and restoring the mem-
ber to normal position thereafter.

6. In combination with a vehicle frame and a
body tiltably mounted thereon, a lock for hold-
ing the body upright comprising a stop member
15 on the body and a pair of independently spring-
projected latch bolts between which said stop is
closely confined in locking position, together with
guide means for said bolts carried on the frame,
said lock including means for automatically re-
tracting one of the bolts to admit the stop be-
20 tween them as the body is tilted into upright
position; said guide means including a guide
member and a rod on which it is slidably carried
with means securing the rod to the frame, and
25 spring means permitting limited lateral move-
ment of the guide member on the rod in response
to the encounter of the stop and the other bolt
and tending to return said guide means to nor-
mal position thereafter.

30 7. In combination with a vehicle frame struc-
ture and a body structure tiltably mounted there-
on, a lock for holding the body upright comprising
a stop member secured to one of said struc-
tures and a pair of independently spring-pro-
jected latch bolts between which said stop is

5 closely confined in locking position, together with
guide means for said bolts carried on the other
of said structures, said stop and bolts having
surfaces formed to cooperate camwise so that one
of the bolts is forced back by encounter with the
stop to admit the stop between them as the body
is tilted into upright position, a member on which
10 said guide means is mounted for limited lateral
movement in response to the encounter of the
stop and the other bolt and spring means per-
mitting such lateral movement and tending to re-
turn the member to its normal position there-
after.

8. In combination with a vehicle frame struc-
ture and a body structure tiltably mounted there-
on, a lock for holding the body upright comprising
a stop secured to one of said structures and
means on the other structure between which said
stop is closely confined in locking position, said
20 means including a spring-projected latch bolt to
engage one side of the stop and an opposed stop
surface for engaging the opposite side, said lock
including means for automatically retracting
the spring bolt to admit the stop between it and
25 the said stop surface as the body is tilted into
upright position; a guide member with guide
means for said bolt mounted for limited lateral
movement in response to the encounter of the
stop with the stop surface, and spring means per-
30 mitting said limited movement of the guide
means and tending to return the same to normal
position.

ANTHONY W. MOLINARE.
